UNITED STATES PATENT OFFICE.

ROBERT P. SMITH, GEORGE E. DRUM, AND JAMES H. SKITT, OF PHILADELPHIA,
PENNSYLVANIA.

DYEING-MACHINE.

1,077,762.

Specification of Letters Patent.

Patented Nov. 4, 1913.

Application filed October 27, 1911. Serial No. 657,083.

To all whom it may concern:

Be it known that we, ROBERT P. SMITH and GEORGE E. DRUM, citizens of the United States, and JAMES H. SKITT, subject of the King of England, residing at Philadelphia, in the county of Philadelphia and State of Pennsylvania, have invented certain new and useful Improvements in Dyeing-Machines, of which the following is a specification.

The object of this invention is to provide a dyeing machine for dyeing hosiery and other knit goods in a manner that will cause them to be thoroughly impregnated with the dye liquor, and at the same time prevent them from being agitated to an extent to cause them to be roughened or tangled.

Broadly, the invention consists of an outer tank to contain the dye liquor, and an inner cage or receptacle for the goods to be dyed, said inner cage having perforated top and bottom and being reciprocated vertically within the tank to plunge the goods downwardly into the dye liquor for impregnation, and upwardly to create a vacuum or suction within the lower portion of the tank to suck the dye liquor downward through the goods and into the tank.

Reference will be had to the accompanying drawings forming a part of this specification and wherein like numerals of reference designate corresponding parts throughout the several views, in which:

Figure 1 is a plan view of the machine, Fig. 2 is a view in side elevation thereof, Fig. 3 is a longitudinal sectional view through the entire machine, cut on the line 3-3 of Fig. 1, and showing in dot and dash lines one of the covers in open position, Fig. 4 is a view in elevation of the driving end of the machine, Fig. 5 is a vertical sectional view cut on the line 5-5 of Fig. 3, Fig. 6 is a detail view partly in section, showing the worm-drive and the manner in which the guided cross-head extension straddles the shaft of the worm-gear, and Fig. 7 is a sectional detail view of the seals.

The invention comprises a tank or receptacle 1 which contains the dye or other impregnating liquor, and a cage or inner receptacle 2 therein for containing the goods to be dyed, washed or otherwise impregnated. The goods to be impregnated, obviously may be of any nature suitable to the process, though primarily, the invention is

designed for the treatment of hosiery and other knit goods. The cage 2 comprises imperforate side and end walls 3 and transverse imperforate partitions 5 dividing the cage into a series of substantially rectangular compartments, which contain the goods to be treated. The bottom 6 of each compartment is perforated, being preferably constructed of wire screen. The cover 7 of each compartment likewise is perforated, being also preferably composed of wire screen secured in a rectangular frame 8, and these frames 8 are hinged at 9 to the upper portions of the cage ends 3 and central partitions 5. These door or cover frames 8 rest on angle irons 10, secured to the inner walls of the cage and partitions and forming a ledge around each compartment, (see Fig. 5,) and through these doors, the goods to be treated are inserted and removed from the cage. When the cage is constructed to be entirely removed from the tank, the perforated bottoms 6 may be likewise secured in similar hinged frames for unloading from the bottom. For locking the covers, bolts 11 are provided and these bolts pass through the partitions next adjacent the cage ends and through the free ends of the covers which are disposed adjacent the said partitions; the covers on opposite sides of the partitions mentioned last being locked by the same bolts.

The cage is suspended at its ends by means of hanger-brackets 12, each of which embraces the adjacent end and side walls of the cage and projects thereabove. Extending along the upper edge of the end portion of each of said brackets 12, is a reinforcing plate 14 to which is bolted the lateral arms 15 of a cross-head 16. A stub-shaft 17 is socketed into each cross-head and projects therefrom, and to each of these projecting portions is attached the upper bearing-box of a pitman 18. These pitmen each preferably consists of parallel bars, (see Fig. 4,) provided at their opposite ends with adjustable split bearing-boxes 19. The lower bearing-box of each pitman is journaled on a crank or wrist-pin 20 of worm-gear 21, and each of said worm-gears is journaled on a stub-shaft 22 projecting from each end wall of the tank 1 substantially centrally thereof. On opposite sides of the stub-shafts 22, parallel vertical angle bars 24, (see Fig. 6,) are secured to each end wall 110

of the tank, and these form guides for downwardly extending guides 25 of the cross-heads 16, which guides 25 will be observed to be cut-out as at 26, (Fig. 6,) to straddle and thereby clear the shaft 22.

5 Across the ends of the tank 1 extends shafts 27 and 28, one at each end, these being journaled respectively in bracket bearings 29 and 29'. Each of the shafts 27 and 28 is provided with a housed worm 30 meshing with the lower portion of the adjacent worm-gear 21. Motion is transmitted from the shaft 27 to the shaft 28 through a shaft 30' journaled longitudinally to the tank in bearings 30'. The opposite ends of the shaft 30' are equipped with bevel-gears 31 which mesh with similar gears 32, one on the adjacent ends of the shafts 27 and 28. Parallel with the shaft 27 is a main drive 10 shaft 33 also journaled in the bearing brackets 29 and provided with fast and loose belt pulleys 34 and 35 respectively, from one to the other of which the belt (not shown) is shifted by the shifter 36. Motion is imparted 15 from the shaft 33 to the shaft 27 through spur-gears 37 and 38 on the said shafts respectively.

Secured by means of bolts 40 to the outer faces of the walls 3 of the cage and extending longitudinally thereof, are substantially 20 U-shaped female packing members in the form of channel-bars 41 of less transverse dimension than the space between the walls 1 and 3 of the tank and cage respectively, 25 (see Figs. 3 and 7.) Channel-bars 42 of corresponding transverse dimension also constitute substantially U-shaped male packing members and have their flanges 44 slidably fitted within the flanges 45 of the 30 channel-bars 41, and the outer faces of these bars 42 slidably engage the inner walls of the tank 1. Surrounding the openings in the bars 41 for the bolts 40, are channel-bosses 46 located within the channels of the 35 said bars 41, and surrounding these bosses are coil springs 47 bearing at their opposite ends against the channel-bars 41 and 42 to normally force the same apart. The end 40 channel-bars 41 and 42, it will be observed, 45 are disposed in different planes from the planes of the side channel-bars, being preferably thereabove. All of the bars extend beyond the corners of the cage practically to the walls of the tank, and the ends of the 50 end-bars 41 overlap the ends of the bars running along the sides of the cage.

55 The dye liquor, water, or other impregnating liquor is admitted to or drawn from the tank through the pipe 50 leading into the tank bottom, (see Fig. 3.)

60 In operation, the goods or materials are placed within the compartments of the cage through the openings controlled by the hinged covers 7, and the covers then secured 65 by the bolts 11. The goods are compacted

so as not to move about in the compartments to become roughened or tangled, yet loose enough to insure thorough penetration thereof by the dye or other impregnating liquor. Power is then applied to the described gearing to set the same into operation. As the worm-gears 21 rotate, their wrist-pins 20 operate the pitmen 18 to vertically reciprocate the cross-heads 16 and with them the cage 2. Canting of the cage 70 is prevented by the downward extensions 25 of the cross-heads slidingly operating in the guides 24, and as the cross-heads are operated in unison, both ends of the cage 2 are correspondingly raised and lowered in unison. The operation of the cross-heads causes the cage to reciprocate vertically in the tank. This action, when the cage is moving downwardly, plunges the goods into the liquor which has previously been admitted into the tank, causing the liquor to pass upwardly through the foraminous cage bottom and through the goods from the under side to the uppermost side of the goods. When the cage reaches the bottom of the 75 tank, the action reverses; the cage begins to rise and lift the goods. This creates a suction or partial vacuum on the under side of the cage due to the expandable channel-bars 80 41 and 42 sealing the space between the tank and cage, and this suction draws the liquor downwardly through the goods and back into the tank. Practically all of the liquor contained in the tank passes through the 85 goods in the cage. The constant movement 90 of the cage up and down causes the dye or other liquor to pass through the goods in both directions which is believed to be one of the most practical and successful methods of dyeing. The machine does not have the 95 fault of roughening or tearing the goods, particularly the knit goods.

The channel-bars 41 and 42 besides serving the function of seals, serve as cushioning elements in that they absorb any material lateral vibration of the cage and also serve as automatic centering means for holding the cage at all times centrally of the tank, particularly when lost motion results from constant use.

Having fully described the invention, what is desired to be secured by Letters Patent is:

1. In a dyeing machine of the class described, an outer tank to contain the dye liquor, an inner receptacle to contain the goods, means for reciprocating the inner receptacle, a shaft on each end of the tank, gearing mounted thereon and having operative connection with the said means, and guides extending from said means and being cut-out to straddle the said shafts, and operating means for the gearing.

2. In a dyeing machine of the class described, an outer tank to contain the dye

liquor, an inner receptacle to contain the goods, a shaft at one end of the tank, a worm thereon, a worm gear meshing therewith, a crank on the worm gear, a pitman having connection with said crank and said receptacle to reciprocate the latter in said tank, a shaft on the end of the tank mounting said worm gear, a guide provided for the tank and having a cut-out portion straddling said last shaft, and operating means for the said first shaft.

3. In a dyeing machine, a liquid receptacle, a goods receptacle therein, a U-shaped packing member, a second packing member telescoping therein, and spring means between said packing members, one of said members being secured to the sides of one of the receptacles and the other packing member slidably engaged with the sides of the other receptacle.

4. In a dyeing machine, a liquid receptacle, a goods receptacle therein, a U-shaped packing member, a male packing member telescoped in the channel thereof, the first member being provided with channel bosses, 25 fastening means passing through the bosses and securing said member to one of the receptacles, and springs surrounding the bosses and bearing against the male member, the male member being slidably engaged with the sides of the other receptacle. 30

In testimony whereof we affix our signatures in presence of two witnesses.
